Primary Examiner — Leanne Was-Englehart*(74) Attorney, Agent, or Firm* — Pearl Cohen Zedek
Latzer Baratz LLP(57) **CLAIM**

The ornamental design for a void former, as shown and described.

DESCRIPTION

FIG. 1 is a side view thereof;
FIG. 2 is a top view thereof;
FIG. 3 is a bottom view thereof;
FIG. 4 is a front elevation view thereof; and,
FIG. 5 is an isometric view thereof.
The broken lines depict portions of the void former that form no part of the claimed design.
